**HAND TOOLS FOR INSTALLING TACKS
AND THE LIKE**

Albert E. Newton, Beverly, Mass., assignor to United Shoe Machinery Corporation, Boston, Mass., a corporation of New Jersey

Filed June 13, 1963, Ser. No. 287,541
2 Claims. (Cl. 227—132)

This invention relates to the provision of impact tools, and more especially to hand-held tackers and the like. Although the invention is herein illustrated as embodied in a low cost tacker which is easily manipulated and adapted automatically to feed a strip of the successive tacks to be inserted, it will be understood that in various aspects application of the invention is not thus limited but may be utilized in other devices requiring similar impact action.

Vast quantities of small components or fasteners such as tacks are being installed, usually in crowded or restricted work localities. For this work it is highly desirable that each insertion of a series be effected manually and accurately in a single operating stroke, that this tool be easily operable to exert impact in any selected direction, and that the tool be of simple structure to lend itself to low cost manufacture. Manually operable fastener inserting devices have, of course, hitherto been provided employing a driver movable in an inserting direction against the resistance of a return spring. It is acknowledged, too, that prior power tools have embodied spring actuated drivers wherein the potential energy of a loaded spring has been released at the will of an operator, for instance at his operation of mechanical latch means as by a trigger. With these considerations and earlier designs in mind, it is a primary object of this invention to provide an economical hand-operated fastener inserting tool of the general type indicated having improved, simple means for augmenting and sharpening the striking power of the driver.

It is a further and more specific object of the invention to provide a reliable, lightweight tacker having a mainly hand-actuated driver adapted to insert tacks from a supply strip, retraction of the driver between insertions being effective to advance into operating position the next strip-mounted tack to be driven thereby.

To these ends, and in accordance with a novel feature of the invention, there is provided an impact type fastener inserting tool comprising in telescoping relation, a body including a nozzle adapted to be held against a work piece, an inner member movable to actuate a driver in the nozzle, an outer operating member, yieldable means connecting the outer member and the inner member for moving the latter in one direction to cause the driver to drive a fastener through the nozzle and into the work piece, and a magnet means for restraining the inner member against movement in the one direction to increase potential energy in the connecting means until the operating force of the outer member in the one direction overcomes the restraining influence of the magnet means, and the operating force being applied to the outer member is thereupon augmented by sudden release of the energy stored in the yieldable connecting means and transmitted through the driver to the fastener.

As herein shown, for purposes of economic assembly, the driver is a straight rod having one end directly secured to an end of the inner member and aligned with the nozzle,

2

and a latch plate cooperative with the magnet means is carried between a shoulder formed on the rod and the mentioned end of the inner member. Preferably for devices required to exert relatively small impact, as in the case of tack inserting, or merely punching holes in light work pieces such as paper, the magnet means is one or more permanent magnets which may be affixed to the tool body. It will be appreciated, however, that it is within the scope of this invention to substitute an electromagnet for the permanent magnet means when desired. Also, although not necessarily thus limited, the yieldable means operatively connecting the outer and inner members is shown as a compression spring.

In order to enable the illustrative tool rapidly to insert successive fasteners, it is adapted to feed them by means of indexable sprockets meshing with a tape or strip carrying a roll of the fasteners. For this purpose and in keeping with a further feature of the invention, pawl mechanism operative on the return or inoperative stroke of the inner member, which in effect is integral with the driver and the latch plate, is employed to index the sprockets to advance the fastener next to be inserted into position to be engaged by the retracted driver. Though this invention is not limited to use with any particular tack strip, there is shown herein a preferred form of strip which is more fully disclosed in a copending application, Serial No. 289,828, filed June 24, 1963, in my name.

The above and other features of the invention together with novel details and combinations of parts will now be more particularly described in connection with an illustrative embodiment and with reference to the accompanying drawings thereof, in which:

FIG. 1 is a view in elevation of a hand-held tacker in its normal inoperative condition and provided with automatic tack feed;

FIG. 2 is a longitudinal section on a larger scale of the lower portion of the tacker shown in FIG. 1;

FIG. 3 is a view on the lower portion of the tacker shown in FIGS. 1 and 2 but at right angles to these views to clarify mechanism for feeding a tack strip;

FIG. 4 is a view corresponding to FIG. 2 but showing the parts at a later stage in a cycle of operations, namely when a driver of the tool has completed its inserting stroke;

FIG. 5 is a transverse section taken on the line V—V of FIG. 1 and looking in the direction of the arrows; and

FIGS. 6—8, inclusive, show one possible tack strip usable in the tacker, the views respectively being in plan, side elevation, and in section.

In the drawings the tool comprises an elongated hollow casing or body 10 which may be generally square in section and provided at one end with a radially slotted nozzle 12 having an exit bore 14 for fasteners such as tacks T to be inserted. In telescoping arrangement with

the body 10 is an outer operating member 16. It has an internal end closure 18 and an external cap 20 preferably of rubber to cushion fastener inserting forces to be exerted manually and axially thereon. Also in telescoping relation to the body 10 is an internal tubular member 22.

For reasons later explained the members 16, 22 are yieldably connected for relative axial sliding movement by a compression spring 24 one end of which abuts the closure 18 and the other end of which engages an end portion 26 of the member 22. It will accordingly be understood

that, upon bringing the nozzle 12 to bear endwise upon a locality of a work piece to be tacked, an operator may axially bear on the cap 20 to cause a rod or driver 28 (FIGS. 2-4) secured at one end, as by peening to the portion 26, to be thrust axially into the bore 14.

Recognizing that a sudden blow by the driver on the head of a tack, sharper than can manually be dealt especially when operating in restricted space, is desirable, means next to be described is provided for automatically modifying the yieldable relation between the members 16, 22. A permanent magnet 30, or if desired a series of such magnets is fixedly mounted, usually externally of the body 10, the outer operating member 16 being longitudinally slotted to avoid interference with magnet supporting tangs 32, 34 struck from and projecting out of the body. The longitudinal position of the magnet along the body is selected so that, when the tool is in its normal inoperative condition shown in FIG. 2, the driver 28 is held axially retracted from the nozzle 12, and from the tack to be inserted, by a latch plate 36 engageable with and attracted by the magnet and held clamped between a shoulder 38 formed on the driver and the end portion 26, the spring 24 then being under relatively light compression. For retaining the spring 24 thus precompressed as shown in FIG. 2, a retaining band 39 (FIGS. 1, 5) welded to the lower outer end of the member 16 is retractable therewith to abut a crossbar portion of the plate 36 and thus move it into initial engagement with the magnet 30. Although not essential to returning the plate 36 to its initial or latched position wherein the magnet 30 contacts and yieldably retains the retracted plate, since such return is normally easily effected manually, there preferably is provided a return spring 40 (generally weaker than the spring 24) for aiding in moving the plate, after an insertion, back into the effective field of the magnet. As noted in FIGS. 2 and 4 the spring 40 is mounted on the driver with one end normally abutting a bracket 42 integral with and inturned from the body 10.

The tool is adapted to insert the tacks T successively from a mounting strip S which is automatically fed by means next to be explained. A pair of spaced sprockets 44, 44 is rotatably supported on a pin 46 journaled in the body 10, the perimeters of the wheels having teeth formed to mesh with a plurality of corresponding notches formed in the margins of the strip as it progresses in a partly circular end portion of a raceway 48 secured to the body 10. For convenience in initially loading the strip into the tool and clearing any jam arising during operation, the body 10 is open on one side to expose several of the teeth of each sprocket wheel, as shown at 50 in FIGS. 2 and 4, for turning by thumb. In order to index the wheels 44 mechanically and thus advance successive endmost tacks T, next to be inserted, into alignment with the driver, a pawl 52 is secured at one end to the inner member 22 and/or the plate 36 and formed at its other end with a tooth 54. The latter is provided with a cam portion 56 disposed ineffectually to deflect the pawl during an inserting stroke upon engagement with one of the teeth 58 of a ratchet wheel 60 integrally adjacent to a hub of one of the sprocket wheels 44. In the course of subsequent retraction of the operating member 16, resultant retraction of the inner member 22 together with the pawl causes its tooth 54 to engage and index the one tooth 58 the distance between successive teeth 58. A spring detent 62 secured to the body 10 and having an inner end adapted yieldably to mesh with successive biased teeth on a ratchet wheel integral with the other sprocket wheel, holds the sprocket wheels against clockwise rotation (as seen in FIGS. 2 and 4) more than one tooth at a time. This indexing corresponds, of course, with the spacing of successive tacks mounted in the strip S.

Operation of the device will now be briefly reviewed. Having threaded a tack strip in the raceway 48 and manually turned the wheels 44 to advance the endmost tack to

a position between the exit bore 14 and the driver 28 as shown in FIG. 2, the nozzle 12 is held against the work piece to be tacked. An operator then strikes or simply bears axially on the cap 20 to telescope the member 16 on the body 10. This tends further to compress the spring 24 to store potential energy therein as its bodily movement in an axial direction is resisted by the restraining influence of the magnet 30 on the plate 36. The strength of the magnet selected will depend in large measure on the nature of the spring 24 and on the force required to effect full insertion of the fastener. Thus in the initial portion of the axial inserting movement of the driver 28, and perhaps nearly up to the instant of its engagement with the head of the tack to be driven, the inner member 22 and the plate 36 are being yieldingly displaced relatively to the magnet 30 by direct manual force until, suddenly the magnetic forces resisting separation of the plate abruptly fail and the spring 24 is no further restrained. At this instant manual operating force is exceeding magnetic attraction on the plate 36. The energy of this compressed spring is at once added automatically to that being manually imparted to the driver to force it against the tack and smartly drive it from the strip, through the nozzle bore, and into the work. Relative retraction of the outer member 16 and the driver from its terminal position shown in FIG. 4 and determined by inturned flanges 64, 66 of the body 10, is facilitated by the return spring 40 which has become compressed by confinement between the bracket 42 and the displaced plate 36. The next tack to be inserted is indexed into operating position by the retractive movement of the member 16 carrying with it the inner member 22 and the pawl 52 as above described.

In addition to providing a compact relatively lightweight easily maneuverable tool it will be clear from the foregoing description of an exemplary form of the invention that the parts are few in number and not likely to get out of order. In particular the novel device may be relied on to wear well, there being no appreciable frictional wear on the plate 36 and the magnet itself being subject to little if any deterioration in use. Moreover an operator is relieved of any necessity to take action to release the compressed spring 24.

Having thus described my invention, what I claim as new and desire to secure by Letters Patent of the United States is:

1. In a hand-held fastener inserting tool, a body having an end portion through which fasteners are to be driven, an outer and an inner member slidably mounted with respect to the body for movement toward and from its end portion, one of the members being adapted to be manually operated, a driver connected to the other member and arranged to be thrust into the end portion of the body in response to manual operation of the one member in a predetermined direction to eject a fastener for insertion, a spring compressible by said operation of the one member and releasable to exert an inserting force on the driver, a latch plate affixed to the driver, and a magnet secured circumferentially on the body for cooperative engagement with the latch plate, the magnet being initially operative during the operation of said one member to restrain the latch and an end of the spring to increase potential energy of the latter, continued operating movement of the one member causing the release of said energy to increase impact of the driver on the fastener.

2. In a hand-held fastener inserting tool, a body having an end portion through which fasteners are to be driven, an outer and an inner member slidably mounted with respect to the body for movement toward and from its end portion, one of the members being adapted to be manually operated, a driver connected to the other member and arranged to be thrust into the end portion of the body in response to manual operation of the one member in a predetermined direction to eject a fastener for insertion, a spring compressible by said operation of the one member and releasable to exert an inserting force on the

driver, a latch plate affixed to the driver, a magnet secured circumferentially on the body for cooperative engagement with the latch plate, and a retaining member secured to the manually operable member for retracting the plate for contact with the magnet and holding the spring precompressed, the magnet being initially operative during the operation of said one member to restrain the latch and an end of the spring to increase potential energy of the latter, continued operating movement of the one member causing the release of said energy to increase impact of the driver on the fastener.
